MERTON W. TAYLOR, OF WEST NEW YORK, NEW JERSEY, ASSIGNOR TO ALUMINUM SCREW MACHINE PRODUCTS COMPANY, OF EDGEWATER, NEW JERSEY, A CORPORATION OF NEW JERSEY.

HAIR CURLER.

Application filed October 27, 1928. Serial No. 315,375.

This invention relates to a hair curler and more particularly to a hair curler adapted to be used in connection with permanent hair-waving means.

5 In curling or waving hair, a tress or plurality of strands of hair is tied together by means of a string adjacent the scalp and then wound spirally on a mechanism, thus preparing it for the necessary subsequent treatments. Various devices have been devised 10 for winding the hair as just described. These devices usually included a tubular member on which the hair was spirally wound or twisted, a rotatable tip member adapted to 15 engage and twist the hair and means to rotate said tip member. In the curling or twisting of the hair with these devices, it was, of course, obvious that the hair must be twisted in one direction whereby it could be tightened 20 to any desired degree. To secure this result, various means such as coil springs were suitably disposed in the device permitting rotation of the tip in one direction and preventing rotation in the opposite direction. Oftentimes, the operator manipulated the device in 25 the wrong direction, whereby, due to the resistance offered by the spring, the latter was deformed and rendered ineffective.

I have found that I can overcome this disadvantage by constructing the cap member, 30 through which rotation is imparted to the tip member, in such a manner that, when rotated in the wrong direction, it will unscrew itself without deforming the spring or putting any substantial strain thereon.

It is, therefore, an object of this invention to provide a hair curler having means manually operated for rotating the tip in one direction only, said means becoming ineffective 40 and unscrewing itself when rotated in an opposite direction.

Another object of this invention is to provide a hair curler having spring means for permitting the rotation of the tip member in one direction only, and means whereby said spring means is not substantially strained or deformed when the device is operated in the opposite direction.

Further objects will appear from the following description, appended claims and the accompanying drawing in which:

The figure illustrates a section of the device constituting this invention.

Referring now to the drawing wherein a device constituting this invention is illustrated, the reference numeral 1 designates a tubular member on which the tress, lock or strands of hair adapted to be curled is wound. Rotatably mounted in one end of the tubular member 1 is the reduced end 2 of a bifurcated tip 3. Screwed into the reduced end 2 of the tip member 3 is a rod 4 which extends through the interior of the tubular member 1. The other end of the rod 4 is screwed into one end of a sleeve 5 disposed within the tubular member 1, whereby rotation imparted to the sleeve 5 is transmitted to the tip 3. In order to permit rotation of the tip 3 in only one direction, one end of a coil spring 6 disposed within the tubular member 1 is secured 55 to the sleeve 5 in any suitable manner. The other end of the sleeve 5 extends beyond the extremity of the tubular member 1 and is threaded so as to receive a manually rotatable cap or nut 7 through which rotation may be 60 imparted to the sleeve 5. The cap 7 is formed with a double threaded bore 8 whereby it may be screwed on to the sleeve 5. Due to this 65 threading the cap, when rotated in one direction, will rotate the sleeve 5 and therefore 70 the tip 3. If, however, the cap is rotated in the opposite direction, it will unscrew itself. 75

In the curling of the hair it is desirable that there be no open joints occasioned by the axial movement of the parts or otherwise, whereby the hair may be gripped and/or torn and through which the preparations used in the treatment of the hair may enter into the interior of the device. With this in view a spring 9 is positioned with 80 one end thereof bearing against the shoulder 10 formed in the cap 7 and the other end bearing against a shoulder or bearing member 11 formed or disposed on the tubular member 1. By means of this spring the 85 tubular member 1 is constantly urged forward, thereby taking up any axial movement between the cap 7, tubular member 1 and tip 3.

In operation, after a tress of hair has been 90 properly tied, it is positioned in the slot of the tip 3 and the cap 7 manually rotated. Due to the sleeve 5 and rod 4, the rotation of the cap 7 is transmitted to the tip 3 whereby the hair is twisted and spirally wound on 95 the tubular member 1. If, perchance, the cap 100

7 is rotated in the wrong direction, due to its construction it will unscrew itself without any substantial deformation or placing any strain on the spring 6 which prevents rotation of the sleeve 5, and therefore the tip 3, in the wrong direction. At the same time the spring 11 will immediately expand and take up the movement of parts. In addition to this, the spring 9, since it constantly exerts a pressure on the shoulder or bearing member 11, will always urge the tubular member 1 forward, thus taking up any axial movement between the tubular member 1 and the tip 3, and always maintaining a tight, closed joint therebetween.

Since it is obvious that various changes may be made without departing from the invention, it is to be understood that the invention is not limited to the specific details above described except as set forth in the appended claims.

I claim:

1. A hair curler comprising a tubular member, a rotatable tip mounted on one end thereof, a rotatable sleeve mounted in the other end of said tubular member, means connecting said tip and sleeve whereby rotation of said sleeve is transmitted to said tip, a cap screwed on said sleeve and having threads

so disposed that, when rotated in one direction, it will rotate said sleeve, and when rotated in the opposite direction it will unscrew itself. 30

2. A hair curler comprising a tubular member, a rotatable tip disposed on one end thereof, a rotatable cap disposed on the other end and operatively connected to said tip, said cap having means permitting rotation thereof in one direction and causing it to unscrew itself when rotated in the opposite direction, 40 and means for taking up the axial movement between said cap, tubular member and tip. 35

3. A hair curler comprising a tubular member, a rotatable tip mounted on one end thereof, a rotatable sleeve mounted in the other end of said tubular member, means connecting said tip and sleeve whereby rotation of said sleeve is transmitted to said tip, a cap screwed on said sleeve and having threads so disposed that, when rotated in one direction, it will rotate said sleeve, and when rotated in the opposite direction it will unscrew itself, and means for taking up the axial movement between said cap, tubular member and tip. 45 50 55

In testimony whereof, I have affixed my signature to this specification.

MERTON W. TAYLOR.
